Primary Examiner — Karen S Acker

Assistant Examiner — Steven B Reinholdt, Jr.

(74) Attorney, Agent, or Firm — Ward and Smith, P.A.;
Ryan K. Simmons(57) **CLAIM**

The ornamental design for a food container lid having dual condiment container receptacles, as shown.

DESCRIPTION

FIG. 1 is a perspective view showing my new design;
 FIG. 2 is a top plan view thereof;
 FIG. 3 is a bottom plan view thereof;
 FIG. 4 is a front elevation view thereof;
 FIG. 5 is a rear elevation view thereof;
 FIG. 6 is a left side elevation view thereof; and,
 FIG. 7 is a right side elevation view thereof.
